(57) **CLAIM**

The ornamental design for a drainage component, as shown and described.

DESCRIPTION

FIG. 1 is a perspective view of a first embodiment of a drainage component showing our new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a perspective view of a second embodiment of a drainage component showing our new design;

FIG. 9 is a front view of FIG. 8;

FIG. 10 is a rear view of FIG. 8;

FIG. 11 is a first side view of FIG. 8;

FIG. 12 is a second side view of FIG. 8;

FIG. 13 is a top view of FIG. 8; and,

FIG. 14 is a bottom view of FIG. 8.

The dash-dash-dash broken lines in the Figures are for the purpose of illustrating unclaimed portions of the drainage component and form no part of the claimed design. The second embodiment of the drainage component is shown with a symbolic break in a length of the design, the symbolic break indicated by dash-dot-dash lines that form no part of the claimed design. The appearance of any portion of the
